(57) **CLAIM**

I claim the ornamental design for a rechargeable battery with universal serial bus (USB) connector, as shown and described.

DESCRIPTION

FIG. 1 is a front elevation view of a rechargeable battery with universal serial bus (USB) connector, showing my new design;

FIG. 2 is a left-side elevation view thereof;

FIG. 3 is a rear elevation view thereof;

FIG. 4 is a right-side elevation view thereof;

FIG. 5 is a top plan view thereof;

FIG. 6 is a bottom plan view thereof; and,

FIG. 7 is a left-side view thereof, with the cap removed exposing the universal serial bus connector, showing a condition of use.
